VETERINARY OBSTETRICAL INSTRUMENT

Herbert J. Larson, Fergus Falls, Minn.

Application February 14, 1952, Serial No. 271,598

6 Claims. (Cl. 128—352)

1

The herein disclosed invention relates to veterinary obstetrical instruments and has for an object to produce an instrument particularly suited for assisting in the delivery of pigs.

Another object of the invention resides in providing an instrument having a snare for engagement about the neck of the pig and in further providing means by which the pig is held from being pushed back into the sow during the application of the snare to its neck.

A further object of the invention resides in constructing the instrument with forceps operable independently of the snare and adapted to be applied to the snout of the unborn pig to hold the same in position while the snare is being supplied about the neck of the pig.

A still further object of the invention resides in constructing the instrument with a tubular shank having a head mounted on the end of the same and in forming the head with outwardly divergent guideways in which a number of arms may be disposed and guided for outwardly diverging movement and in further attaching the snare to the end of said arms.

An object of the invention resides in constructing the head with other guide means disposed inwardly of said first named guides and in further providing a number of fingers guided by said second named guide means for movement in an outwardly diverging relation and in further forming on the ends of said fingers claws for engagement with the snout of the unborn pig.

A feature of the invention resides in providing operating means for both the snare and the forceps disposed exteriorly of the shank and connected to the said arms and fingers and adapted to be independently operated.

A feature of the invention resides in constructing the instrument with shifting members disposed in said shank and to which the said arms and fingers are attached, said shifting members being guided for axial sliding movement along said shank and being attached to said operating means.

Other objects of the invention reside in the novel combination and arrangement of parts and in the details of construction hereinafter illustrated and/or described.

In the drawings:

Fig. 1 is a longitudinal sectional view of a veterinary obstetrical instrument with the parts in retracted position and taken on line 1—1 of Fig. 4.

Fig. 2 is a view similar to Fig. 1 with the forceps extended and showing the construction of the operating means for the snare and with the

2

structure rotated through an angle of 90 degrees.

Fig. 3 is an end elevational view of the structure shown in Fig. 1.

Fig. 4 is a cross sectional view taken on line 4—4 of Fig. 1.

Fig. 5 is a view similar to Fig. 2 showing the snare in extended position and the forceps in a position adapted to grip the snout of the unborn pig.

10 The veterinary obstetrical instrument shown in the drawings comprises a tubular shank having an annular head attached to one end thereof. This head is formed at the outer surface thereof with outwardly flaring guideways in which are received arms extending into the shank and attached to a shifting member slidably axially along the shank. The said guideways guide the arms for movement in outwardly divergent relation with respect to one another. The ends of the 15 arms are provided with eyes through which a snare is threaded. An operating member disposed exteriorly of the shank and connected to the shifting member serves to move the arms from extended to retracted position and vice versa. The head is formed with a bore through which a number of fingers extend. These fingers are attached to a shifting member also movable axially within the tubular shank. These fingers are formed at the ends of the same with claws 20 and the said fingers are adapted to spread upon being moved outwardly by the shifting member and to grip the snout of the unborn pig when the shifting member is retracted. The shifting member has attached to it operating means disposed exteriorly of the shank and connected to said shifting member. The forceps and snare are independently operable.

25 The instrument shown consists of a tubular shank 10 threaded at both ends. In one end of the shank is screwed a head 11 having a threaded neck 12. In the other end of the shank is screwed a cap 13 having a threaded neck 14. The head 11 supports a snare 15 and forceps 16 which latter is disposed within the confines of the former and which are independently operable. These parts will now be described in detail.

30 The snare 15 is supported by means of four arms 17 which are constructed of ribbon type spring material and which are disposed partly within the bore 18 and shank 10. These arms are secured by means of screws 19 to a shifting member 20. Shifting member 20 is cylindrical in form and is provided with axially extending flats 21 on which the arms 17 rest. The shifting member 20 is slidable within the bore 18 of shank

10. For the purpose of manipulating the snare the following construction is used. The shank 10 is formed with a longitudinally extending slot 22. A knob 23 is mounted on the exterior of the shank 10 and overlies the slot 22. Knob 23 is attached to the shifting member 20 by means of a screw 24 which extends through said knob and is screwed into said shifting member.

The head 11 is frusto conical in form and has an outer conical surface 25 and a bore 26 extending therethrough. The outer end of the said bore has a flare 27. In the surface 25 is formed four guideways 28 in which the four arms 17 are disposed. These guideways serve to cause the arms to diverge outwardly from the head 11 when the shifting member 20 is moved toward the head 11 as shown in Fig. 5.

The snare 15 consists of a cord, cable or piece of wire which is threaded through eyes 29 formed on clips 30. These clips are attached to the ends of the arms 17 by means of rivets 31. The snare 15 may travel freely in the said eyes and the ends 32 and 33 of the snare may be drawn taut to close the snare about the neck of the unborn pig when the arms 17 are properly positioned.

The forceps 16 consists of four fingers 34 constructed of resilient wire which are all mounted in the bore 18 of shank 10. These fingers are attached at one end to a shifting member 35 also disposed within the bore 18 of shank 10. These fingers also extend through the bore 26 of head 11. The ends of the fingers are formed with claws 36 which are directed toward one another as best shown in Figs. 1 and 2. The fingers 34 are normally spread outwardly so that when the shifting member 35 is moved toward the head 11 the fingers take the position shown in Fig. 2.

The shifting member 35 has attached to it and forming part thereof, a rod 37. Rod 37 and the fingers 34 may all be brazed or soldered to the shifting member 35 or secured thereto in any other suitable manner. The rod 37 passes through a bore 38 in the shifting member 20 and through a bore 39 in the cap 13. On the end of the rod 37 is mounted a button 40 which may be attached to said rod by means of threads 41 formed on the end of the same. This button serves as operating means for operating the forceps 16. A compression coil spring 42 encircles the portion of the rod 37 projecting outwardly beyond cap 13 and is seated at one end against said cap and at its other end against the button 40. This spring normally holds the forceps 16 in the position shown in Fig. 1.

The method of use of the instrument is obvious. The instrument is inserted with the parts positioned as shown in Fig. 1 until the head 11 reaches the unborn pig. The button 40 is next depressed until the forceps 16 are open as shown in Fig. 2 and the claws 36 spaced from one another. In such position the snout of the unborn pig may enter the space between the fingers 34. Upon release of the button 40 the claws 36 grasp the snout of the pig and hold the pig in fixed position. With the pig so held the knob 23 is moved forwardly and the ends 32 and 33 of the snare 15 released so that the snare may be moved to a position approaching that shown in Fig. 5. When the snare 15 is well back of the head of the pig and encircling the same the ends 32 and 33 are drawn taut and the snare firmly attached to the animal. The unborn pig may then be delivered by exerting traction on the ends of the snare and the entire instrument.

The advantages of the invention are mani-

fest. The pig is firmly held in position while the snare is attached. The snare can be easily forced over the pig's head and applied to the pig's neck. Both the snare and the forceps are independently operable so that the forceps may be first attached and the snare subsequently applied. The device can be constructed of fairly small dimensions so the sow is subject to as little discomfort as possible. The instrument can be manufactured at an economical cost and by methods and equipment readily available.

Changes in the specific form of the invention, as herein described, may be made within the scope of what is claimed without departing from the spirit of the invention.

Having described the invention, what is claimed as new and desired to be protected by Letters Patent is:

1. In a veterinary obstetrical instrument, a tubular shank, a head attached to one end of said shank, a shifting member within the shank and slidable along the same, operating means therefor disposed exteriorly of said shank and connected to said shifting member, a plurality of arms connected to said shifting member and when in use extending outwardly through said head and beyond the same, guide means formed in said head for guiding said arms in a manner to cause spreading of the same upon movement of said shifting member toward said head, eyes at the ends of said arms, a snare extending through said eyes and having portions extending along said shank and serving to close the snare, a second shifting member within the shank and slidable relative thereto, operating means therefor disposed exteriorly of said shank and connected to said second named shifting member, a plurality of fingers connected to said second named shifting member and when in use extending through said head and beyond the same, other guide means formed in said head and guiding said fingers to extended positions, said fingers being resilient and being biased to cause spreading of the same upon movement of said second named operating means toward said head, and claws formed on the ends of said fingers.

2. In a veterinary obstetrical instrument, a tubular shank, a head attached to one end of said shank, a shifting member within the shank and slidable along the same, operating means therefor disposed exteriorly of said shank and connected to said shifting member, a plurality of arms connected to said shifting member and when in use extending outwardly through said head and beyond the same, guide means formed in said head for guiding said arms in a manner to cause spreading of the same upon movement of said shifting member toward said head, eyes at the ends of said arms, a snare extending through said eyes and having portions extending along said shank and serving to close the snare, a second shifting member within the shank and slidable relative thereto, operating means therefor disposed exteriorly of said shank and connected to said second named shifting member, a plurality of fingers connected to said second named shifting member and when in use extending through said head and beyond the same, other guide means formed in said head and disposed inwardly of said first named guide means and guiding said fingers to cause spreading of the same upon movement of said second named operating means toward said head, and claws formed on the ends of said fingers, said claws

and fingers operating within the confines of said arms.

3. In a veterinary obstetrical instrument, a tubular shank, a head attached to one end of said shank, a number of arms extending through said head and retractable into said shank and head, guide means formed in said head and disposed angularly relative to said shank and engaging said arms to guide said arms for movement in outwardly diverging directions, a snare carried by the ends of said arms, operating means for said arms disposed exteriorly of said shank and connected to said arms, said operating means serving to extend or retract said arms, a plurality of fingers extending through said head, other guide means in said head and engaging said fingers to guide said fingers for movement in outwardly diverging directions, claws formed on the ends of said fingers and operating means for said fingers disposed exteriorly of said shank and connected to said fingers, said second named operating means serving to extend or retract said fingers, said arms and the structure attached thereto being movable independently of the fingers and structure attached thereto.

4. In a veterinary obstetrical instrument, a tubular shank, a head attached to one end of said shank, a number of arms extending through said head and retractable into said shank and head, guide means formed in said head and disposed angularly relative to said shank and engaging said arms to guide said arms for movement in outwardly diverging directions, a snare carried by the ends of said arms, operating means for said arms disposed exteriorly of said shank and connected to said arms, said operating means serving to extend or retract said arms, a plurality of fingers extending through said head, other guide means in said head and engaging said fingers to guide said fingers for movement in outwardly diverging directions, said second named guide means being spaced from said first named guide means, claws formed on the ends of said fingers and operating means for said fingers disposed exteriorly of said shank and connected to said fingers, said second named operating means serving to extend or retract said fingers, said arms and the structure attached thereto being movable independently of the fingers and structure attached thereto.

50

5. In a veterinary obstetrical instrument, a tubular shank, an annular head attached to one end of said shank, said head having a circular outer surface and a bore, a number of guideways formed in said head at the outer surface thereof and extending in an angular direction with reference to said shank, a number of arms constructed of resilient material received within said guideways and extending through said head and into said shank, operating means disposed exteriorly of the shank and connected to said arms and moving said arms along said guideways and causing the arms to spread upon movement of the operating means toward the head, a snare attached to the outer ends of said arms, said bore having an outwardly flaring portion at its outer end, a plurality of fingers received within said bore and constructed of resilient material and normally biased to cause spreading upon being ejected from said bore, said fingers having claws at the ends of the same and operating means disposed exteriorly of the shank and connected to said fingers for shifting said fingers independently of the movement of said arms.

6. In a veterinary obstetrical instrument, a tubular shank, an annular head attached to one end of said shank, said head having a frusto conical outer surface and a bore, a number of guideways formed in said head at the outer surface thereof and extending along an element of said surface and in an angular direction with reference to said shank, a number of arms constructed of resilient material received within said guideways and extending through said head and into said shank, operating means disposed exteriorly of the shank and connected to said arms and moving said arms along said guideways and causing the arms to spread upon movement of the operating means toward the head, a snare attached to the outer ends of said arms, said bore having an outwardly flaring portion at its outer end, a plurality of fingers received within said bore and constructed of resilient material and normally biased to cause spreading upon being ejected from said bore, said fingers having claws at the ends of the same and operating means disposed exteriorly of the shank and connected to said fingers for shifting said fingers independently of the movement of said arms.
